Eleazer Thomas,

UNITED STATES PATENT OFFICE.

ELEAZER THOMAS, OF PAWTUCKET, RHODE ISLAND.

MOLDER'S FLASK.

SPECIFICATION forming part of Letters Patent No. 297,646, dated April 29, 1884.

Application filed February 6, 1884. (No model.)

To all whom it may concern:

Be it known that I, ELEAZER THOMAS, of Pawtucket, Providence county, Rhode Island, have invented certain new and useful Improvements in Molders' Flasks, of which the following is a specification, reference being had to the accompanying drawings, making part thereof.

The object of this invention is to improve molders' flasks by providing them with sand frames or bands, and with corner-supports and adjusting-screws or equivalent devices to hold said frames in position in the flask; also, to provide such sand-cleats with cross-bars adjustable up and down, or made reversible therein, or having both these peculiarities. The first of these improvements—that is, supplying the flask and sand-frame with clamping-screws—enables me to make the frame sufficiently loose within the flask to permit its ready insertion and removal without opening the flask, and yet to hold the frames, sand, and mold firmly in place, although the flask may be roughly handled or rolled over or around upon the bench, floor, or ground in the foundry. The second part of my invention gives to the sand-mold in the flask intermediate support, permitting the parting of the mold at planes other than that of the meeting of the cope and nowel, so that, when the article to be molded demands it, the cross-bars may be placed in a higher or a lower plane than the marginal parts of the cleat, to accommodate the device to the work.

My invention consists in the devices and combinations of devices set forth in the appended claims.

In the drawings, Figure 1 is a plan of part of a flask and its inclosed sand-frame, showing a suitable arrangement of the clamping-screws which secure the latter in position, and also representing one of the cross-bars. Fig. 2 is a vertical section of one edge of the flask and sand-frame at line *x* *x* of Fig. 1, illustrating the adjustable supports of the cross-bar. Fig. 3 is an edge view of part of the sand-frame, showing the slot and screw for adjusting the cross-bar vertically.

A and *B* are respectively the upper and lower portions of the flask, having the usual devices for insuring their proper alignment.

E is the sand-frame—a rectangular marginal band having a vertical outer face to correspond to and fit loosely within the flask, and tapering from its lower edge upwardly,

so as to support the sand packed within it. These frames rest at their corners upon their supports *D*, secured to the flask.

F *F* are clamping-screws, threaded to engage with the sides of the flask, through which they pass, or with nuts fixed therein, and bearing at their points against the vertical outer faces of the band or frame *E*, so as to press it into firm contact with the flask on the side opposite thereto. These screws are provided at one side only, or at one side and one end, leaving the others free for the frame to bear against frictionally, so that the screws used will hold the parts in firm contact until it is desired to remove the flask, when the pressure of the screws will be relaxed.

G is one of the cross-bars, spanning the frame from side to side, made adjustable by any suitable means. The drawings show a convenient arrangement for this purpose. The end of the cross-bar is notched to correspond with similar horizontal notches, *H*, on the inner faces of the band or frame *E*, and screws *K*, passing through countersunk holes or slots *L* formed in the frame, enter the ends 80 of the cross-bars and hold the notched surfaces in close contact, thus fixing the cross-bars firmly to the marginal band. The countersinking of the screw holes or slots prevents contact of the screw-heads with the flask, 85 while the notching gives the bars reliable support, yet allows their adjustment up and down by lateral removal, and insertion in higher or lower notches when the screws are withdrawn.

When desired, the flask may be used with one or more of the cross-bars removed.

Having thus described this improvement of mine in molders' flasks, what I claim as my invention, and desire to secure by Letters Patent, is—

1. In combination with a molder's flask provided with supports *D*, or their equivalents, a marginal sand frame or band and one or more clamping-screws adapted to confine said frame or band within the flask or release it therefrom, substantially as and for the purpose set forth.

2. In combination with a molder's flask, a marginal sand frame or band provided with removable and adjustable cross-bars, substantially as and for the purpose set forth.

Witnesses: ELEAZER THOMAS.
